ATTORNEY

UNITED STATES PATENT OFFICE.

JOHN L. POPE, OF CLEVELAND, OHIO.

DESIGN FOR A SEAT-RISER.

SPECIFICATION forming part of Design No. 14,329, dated September 25, 1883.

Application filed November 11, 1882. Term of patent 14 years.

To all whom it may concern:

Be it known that I, JOHN L. POPE, of Cleveland, in the county of Cuyahoga and State of Ohio, have invented and produced a new and original Design for Seat-Risers, of which the following is a specification, reference being had to the accompanying photograph, forming part thereof.

My invention relates to a novel design for seat-risers; and it consists in certain features of ornamentation, which will be hereinafter more particularly described, and set forth in the claims.

In the accompanying photograph, A represents a flat bar with lugs projecting therefrom at about right angles. Three lugs are shown, the middle one being quite short relatively to the end ones, to which latter the seat proper is attached in the usual and well-known manner. B is another bar, flat on its base and provided about midway of its length with a hole for attachment of the riser to the top rail or board of the wagon by bolts, as usual and well understood. Between these two bars A and B, and formed integrally therewith, will be found my novel pattern or design of ornamentation, which I shall now more particularly describe.

Adjoining the bar or rail A are three curved or arch-shaped ribs, a a a, and two hook-like portions, b b. The ends of the central curved rib or segment terminate in two upwardly-

projecting knob-like portions, c c, while the ends of the other two segments, a a, run down and vanish at points near the hook-like and knob-like portions b c, as plainly shown. 35 The hooks b are terminations of the upper ends of two bars, e, made up of a variety of curves, the lower ends of which bars are cast with the bottom bar or rail, B. From near the roots of these bars e extend upwardly and inwardly 40 branches n, bifurcated at their upper portions, as at o, the bifurcations being curved, and connecting at their extremities with the roots of the segments a and with the inner edges of the crooked bars e. The branches n are made up 45 of two curves, their junctures occurring at the points s s.

What I claim as my invention, and desire to secure by Design Letters Patent, is—

1. A design for a seat-riser, composed of the 50 bars A and B, crooked bars e e, segments a a a, and branches n n, all arranged in substantially the manner shown and described.

2. A seat-riser ornamented substantially as shown and described. 55

In witness whereof I have hereunto set my hand this 3d day of November, 1882.

JOHN L. POPE.

In presence of—

WALTER A. BIDDLE,
GEORGE F. EBERHARD.
